APPARATUS FOR REMOVAL OF ELECTROSTATIC CHARGES FROM THE SURFACES OF MATERIALS OF LOW CONDUCTIVITY BY MEANS OF A STABILIZED ELECTRICAL GLOW-DISCHARGE

Robert Leupi, Sarnen, Switzerland, assignor to G. A. Messen-Jaschin, Sarnen, Switzerland

Filed Mar. 25, 1955, Ser. No. 496,853

Claims priority, application Switzerland Mar. 26, 1954

4 Claims. (Cl. 315—57)

This invention relates to a device of the kind serving to remove electrostatic charges from the surface of ill-conducting materials. It is especially suited to discharge materials that are passing it in the form of ribbons and endless webs but it also permits to remove electrostatic charges from the surfaces of solid immovable or hardly movable objects.

The discharge of the surface is effected by the ions generated by a stabilized electrical low- or high frequency glow-discharge, whereby the stabilization of this form of discharge is obtained in per se known manner by electrical radiation-resistors or intermediate layers. According to recently gained experience it is most important that the electrostatic field surrounding the object to be discharged may deeply penetrate the space of discharge between the electrodes.

The method, per se, is already well known and sufficiently proved.

Up to now, however, no practical design of the electrodes has been found that would have satisfied in practice with respect to operation and moreover ensured a sufficient rapid discharge of the charged objects.

Hitherto designs of electrodes have been proposed and realized where the glowing electrode was equipped by sharp points and surrounded by a tube of insulating material leaving the points free in corresponding openings. The insulating tube has the purpose of a protective device against accidental contact with the high tension electrode and the fine points.

Substantially more effective than these electrodes with points are electrodes having glowing edges or wires, because the number of glowing ions is necessarily proportioned to the area of the glowing surface. In this kind of electrodes the insulating tube serves to receive at least one glowing wire or at least one metal foil that when connected to a high-tension source glows at the outwardly directed edge.

In order to make the discharge of a ribbon running over these glowing portions most effective this ribbon should move along said tube or rod in a very little distance or even slide over it. This is disadvantageous in the case where the tension of the ribbon cannot be kept sufficiently constant, to ensure a constant distance from the tube. Since due to friction of the ribbon on the tube of insulating material a new charge will be generated on the ribbon.

It is an object of the present invention to avoid this disadvantage to a great extent partly by a greater discharging effect, generated by the approaching of a counter electrode and partly in that it is made possible for the field to penetrate deeply in the space of discharge of the stabilizing glow-discharge. This opens the possibility of a substantial simplification and economization of the design.

A further object of the invention is to provide a cylindrical body forming one of the electrodes and serving at the same time as support for at least one metal wire insulated from the support and forming the second electrode, that extends parallel to the axis of the cylinder and exteriorly of the latter.

2

It has been found that not only an asymmetrical position of the glowing wire but also an asymmetrical position of its counter electrode in the insulating body may be of great importance.

In the device according to the present invention therefore the cylindrical body is an insulating body enclosing at least one cylindrical axially directed metallic body parallel to the insulating body and coated by it and filling out a smaller portion of the section of the insulating body, the metallic body being outwardly displaced with respect to the axis of the insulating body in the direction to the glowing wire in such a manner, that only a narrow zone of the insulating body is traversed by the field generating the glow discharge.

By this arrangement two substantial advantages are gained. On the one hand the capacity of the electrode coated by the insulating body may be kept much lower without suffering any loss of field intensity near the glowing wire, and on the other hand in the case of high-frequency operation of the device, the high frequency loss in the insulating body is much smaller, if only one part of the insulating body is traversed by the strong field generating the glow discharge. Both advantages are gained by the fact that the metal cylinder extending parallel to the glow wire is eccentrically arranged in the insulating body filling out only a smaller part of the section thereof.

In order to get a correct screening of the high frequency field emitting from the inner or the counter electrode respectively, the cylindrical body for screening the high frequency field may be surrounded by at least one not glowing grounded metal part, which leaves the grounded glow wire generating ions free. Suitably the not glowing metal part is not arranged nearer to the glow wire than the glow wire is distant from the cylinder, so that the field extending from the material to be discharged is able to penetrate deep enough in the space of discharge between glow wire and counter electrode.

By way of example specific embodiments of the present invention are represented in the accompanying drawings.

Figs. 1 to 4 and 1a to 4a are axial- and cross-sections illustrating four discharging devices according to the invention.

Figs. 5—6 show various arrangements of the high frequency transformer in the device according to Figs. 1—4.

Fig. 7 illustrates the simultaneous application of the high frequency transformer as a mechanical support for a cantilever cylindrical electrode.

Figs. 8, 8a are axial- and cross-sections, respectively, of a first example.

Figs. 9 and 9a are axial- and cross-sections of a second example.

Figs. 10 and 10a are axial- and cross-sections of a modification with respect to Figs. 2, 2a, respectively.

Figs. 11, 11a show in side view and section, respectively, a further modification of the example according to Figs. 9, 9a.

Fig. 12 a side view of a part of the first embodiment of the device.

Fig. 13 a cross-section through the part of the device shown in Fig. 12.

Figs. 14 and 15 a side view and a section of the second example.

In Fig. 1, a convenient embodiment of the device according to the invention is shown. The numeral 1 designates a cylindrical metallic hollow or solid body, which at both of its ends is provided with two metallic supports 2. The latter are insulated from the body by means of insulating portions 3. The supports 2 serve for the attachment of wires 4, which extend parallel with respect to the axis of the cylindrical body 1 and are covered

by a glow-layer as soon as sufficiently high electrical voltage is present between the support 2 and the cylindrical metal body 1 by connecting these parts with a suitable source of voltage. The voltage can be led to the electrode 1 either laterally or axially. In the latter case support 2 and insulating body 3 are provided at one side with at least one axial bore for the reception of a high voltage cable. In order to mount the complete apparatus, brackets or handles are connected to the face sides of the apparatus, i.e. to the metallic supports 2.

The wires surrounding the metallic body and extending in axial direction, form a wire-electrode, which may be earthed. The electrode 1 carrying the voltage is then screened by an earthed wire-electrode, forming a cage and protecting that electrode from being contacted. The separate wires of the wire-electrode glow during operation despite being earthed, since the glow discharge is only dependent of the field erected above said wires and not of the absolute potential of the wires. Also in the case of the Saint Elmo's fire, the luminous objects are connected to earth.

The spacing between two adjacent wires 4 should at least be equal to their distance from the cylindrical electrode 1 in order that the field of the body to be discharged will reach sufficiently into the discharge space of the glow discharge and thereby will be fed with the ions necessary for discharge.

The wire cage-electrode provides an effective protection against touching since the field at the wires will be homogenised upon approach of a hand to the extent that it will no more be sufficient to keep up the glow discharge and no electrifying effects are experienced.

An effective protection of the voltage-carrying electrode can also be achieved with less wires in that according to Fig. 2 the cylindrical metallic body 1 is provided with an insulating layer 5 of good dielectric break-down properties or in that according to Fig. 3 the voltage-carrying electrode is arranged as a conductive layer 6 in a tube 7 of insulating material. In order to prevent flash-overs the ends of the insulating tube 7 can be provided with stoppers of insulating material which are glued into the tube to give a certain break-down safety to the assembly.

Another embodiment of the device is shown in Fig. 4. Here the voltage carrying electrode is formed by a metallic body 8 such as a metal tube, which is only supported by the tube covering portions 9 at both of its ends or insulators, inserted into this tube. Also in this case the tube covering portions may be glued in for break-down safety.

In order not to necessitate a high tension cable for feeding the high voltage, which would be unhandy, suitably high-frequency currents are used, which are transformed in a small Tesla-transformer 10 to high voltage, which transformer may suitably be attached to one end of the device. The coil body of the secondary coil of this Tesla-transformer may at the same time have the mechanical function of one of the insulation coils 3 or 9, respectively, in one of the embodiments according to Figs. 1, 2 or 4, as for instance shown in Figs. 5 and 7. When using a tube of insulating materials the Tesla-transformer 10 is suitably mounted into this tube as shown in Figs. 6 and 7. This provides a certain protection for this transformer against damage and there will be less danger of inadvertently touching said transformer.

In all cases where the wire electrode is connected to earth there will be no difficulties in insulating the feed cable for the primary side of the Tesla-transformer. The feed cable could for instance leave the device at point 11 (Fig. 5) at the foot of the Tesla-transformer.

Since the primary winding of the Tesla-transformer carries only low-voltage with respect to earth, the metallic support 2 of the suspended wire may be fixed at the height of this winding at the tube as shown in Fig. 7 without charging the secondary winding with an additional capacity. In the same manner also the other sup-

port 2 may be fixed on the insulating tube 7 if the tube is extended correspondingly over the voltage carrying electrode at this point. This manner of attachment of the supports 2 has the advantage that the device may 5 suitably be secured at both of its ends by means of brackets or that the tube ends serve at the same time as handles.

In the embodiment according to Figs. 8 and 8a a cylindrical insulating body 12 is provided, which is formed 10 as a round bar. The insulating body 12 is provided with an eccentric longitudinal bore, in which a metallic rod 13 forming one of the electrodes is arranged. By means of end plates 14 two wires 15 diametrically and parallelly extending with respect of the axis of the insulating body 15 are suspended. The wire 15 being shown as situated above the other wire in these figures, serves as glow electrode.

In the embodiment according to Figs. 9, 9a the cylindrical insulating body is formed by a tube 16 in which a cylindrical rod-electrode 18 is eccentrically arranged with 20 respect to the tube 16 but parallel to the axis of the latter by means of the holder 17. Otherwise the construction of the device is the same as in the first described embodiment.

In the modification according to the Figs. 10, 10a of 25 the previously described embodiment, two cylindrical metallic electrodes 18 are diametrically arranged within the tube 16, forming the insulating body and eccentrically with respect to the axis of the latter.

These two metallic electrodes 18 are electrically connected with each other.

In the modification shown in Figs. 11 and 11a the cylindrical insulating body is formed by a two-part tube 19, its two-parts being diametrically opposed to each other. Also in this case a cylindrical metal electrode 18 is eccentrically arranged within this tube. By means of the two-part configuration of the tube 19 longitudinal slots 20 are formed, which permit a further reduction of the high-frequency loss. Thereby the insulating body must naturally fill out a sufficiently large space between the metal electrode and the glow-wire, in order to stabilize the discharge in that space with respect to a spark or arc discharge. It will be understood that also in this case two metallic electrodes 18, corresponding to the modification according to Figs. 10 and 10a might be provided.

Similarly the insulating bodies 12 and 16 of the embodiments according to Figs. 8 to 10 might be provided with longitudinal slots to reduce the high frequency losses.

In all described embodiments the cylindrical metal body 13 and 18, respectively, forming the inner electrode is eccentrically arranged with respect to the axis of the insulating body, and towards the corresponding glow wire 15, such that only a narrow zone of the cross-section of the insulating body will be situated between the metal electrode and the glow wire, which will be penetrated by the strong field generating the glow discharges. Further 55 this metal electrode 13 and 18, respectively, will fill out in all cases only a small portion of the total cross-section of the insulating body.

In order to minimise the glow-losses of the electrode built into the insulated body, these electrodes are given a circular or elliptic cross-section and are provided with ball-shaped end portions.

In Figs. 12 to 14, 21 designates the cylindrical body, which in the embodiments shown, is formed as a tube. Two holding rings 22 are seated on the tube 21 and are 60 axially spaced from each other. Between these holding rings a glow-wire is extended distanced from the outer surface of the tube 21 and parallel with respect to the tube axis by means of screws 23.

In the embodiment according to Figs. 12 and 13 a second wire 24 is extended between the holding rings 22 parallel with respect to the tube axes and diametrically opposed to the first glow-wire. The tube 21 is constituted by an insulating body. In the same diameter as the wire electrodes 24, one of which is formed as a glow-electrode, 75 a counter-electrode formed by a cylindrical metal rod

25 is arranged within the tube 21. The metal rod 25 is distanced from the tube axis and extends parallel thereto. At the rings 22 a screening cover 26 is secured, which surrounds a part of the insulating body 21 in trough-shaped configuration without obstructing thereby the upper glow-electrode 24. The distance of the cover 26 from the insulating body 21 must at least be equal to the distance of the glow-electrode 24 from the insulating body 21. In the embodiment shown the first-mentioned distance is somewhat larger than the second-mentioned distance. The wires 24 and the cover 26 are connected to earth, while the counter electrode 25 carries voltage.

In most cases it will be sufficient to give the remaining spacing 27 (Fig. 13) double the width of the distance between the glow-electrode 24 and the electrode 25 or the insulating body 21, respectively. Thereby the field emitted by the material to be discharged may penetrate sufficiently into the discharge space between the glow electrode 24 and the electrode 25 or the insulating body 21, respectively and it will thus be possible to collect the ions from this space necessary for the discharge of the material.

Tests have shown that in many cases a metallic protecting-cover will already by sufficient, the edge tangent surface of which will just contact the insulating body 21 if the glow electrode 24 connected to earth will extend in the middle of this spacing 27 as shown. In order to prevent glowing of the protecting cover the latter is crimped at its ends 28 with a sufficiently large radius.

In the embodiment according to Figs. 14 and 15 a plurality of metallic wires 29, which are suspended in the same manner as the glow wire 24 between the holding rings 22 and with the same angular spacing with respect to each other or the glow wire 24, respectively, serve as a screen. The metallic wires 29 include a larger radial distance with respect to the tube axis than the glow wire 24 and further their cross-section is larger than that of the glow wire. In this case the tube 21 is made of metal and forms the voltage carrying electrode 29.

It will be understood that also when using a counter-electrode 25 according to Figs. 12 and 13, eccentrically arranged in the insulating body, the screen may be formed by suspended wires 29.

In both embodiments shown, the plane of symmetry extending through the longitudinal axis of the device and through the glow wire 24 will be perpendicular to the plane of the material to be discharged.

The screen metal portion could also be formed by an other suitable apparatus- or machine-part.

I claim:

1. An apparatus for the removal of electrostatic

charges from the surfaces of materials of low conductivity by means of a stabilized electrical glow-discharge comprising a metallic cylindrical body forming an elongated electrode, an insulating member at each end of said body, supporting means carried by each insulating member, and a metallic wire forming a second electrode extended between said supporting means at both ends of said cylindrical body in parallel relation to the axis thereof or exteriorly of said cylindrical body forming the first-mentioned electrode, wherein a high-voltage transformer is mounted between one end of the cylindrical electrode and the adjacent supporting means, in order to generate the voltage required for operating the glow-electrode.

2. An apparatus as claimed in claim 1, in which the secondary of said high voltage transformer is wound on a coil body serving as support for said cylindrical metal body.

3. An apparatus for the removal of electrostatic charges from the surface of materials of low conductivity by means of a stabilized electrical glow-discharge comprising a metallic cylindrical body forming an elongated electrode, an insulating member at each end of said body, supporting means carried by each insulating member, and a metallic wire forming a second electrode extended between said supporting means at both ends of said cylindrical body in parallel relation to the axis thereof exteriorly of said cylindrical body forming the first-mentioned electrode, wherein a high voltage transformer generating the voltage required for operating the glow-electrode is built into one end portion of said cylindrical body formed of insulating material.

4. An apparatus as claimed in claim 3, in which the end of said hollow cylindrical body remote of said transformer is provided with a glued-in stopper for preventing electrical break-down.
